CONTROL DEVICE

Walter S. Landon, Detroit, Mich., assignor to
 Detroit Lubricator Company, Detroit, Mich., a
 corporation of Michigan

Application September 11, 1936, Serial No. 100,293

10 Claims. (Cl. 236—48)

My invention relates generally to control devices and more particularly to control devices for controlling flow of fluid.

One of the objects of my invention is to provide 5 a new and improved actuating mechanism for control devices.

Another object of my invention is to provide in a control device having a valve for controlling flow of fluid, new and improved stop means for 10 limiting movement of the valve.

Another object of my invention is to provide a control device having a new and improved arrangement of the operating parts thereof.

The invention consists in the improved construction and combination of parts, to be more 15 fully described hereinafter and the novelty of which will be particularly pointed out and distinctly claimed.

In the accompanying drawings, to be taken as 20 a part of this specification, I have fully and clearly illustrated my invention, in which drawings—

Figure 1 is a top plan view of a control device, with the cover removed, embodying features of 25 my invention;

Fig. 2 is a view shown in vertical cross section of the device of Fig. 1 and taken along the line 2—2 of Fig. 1;

Fig. 3 is a detailed view of a portion of a valve 30 employed in my device;

Fig. 4 is a detail view shown in cross section and taken along the line 4—4 of Fig. 2;

Fig. 5 is a view shown in vertical central longitudinal cross section of the control device of 35 Fig. 1 and taken along the line 5—5 of Fig. 1;

Fig. 6 is a fragmentary view shown partly in elevation and partly in cross section of structural details of my device and taken along the line 6—6 of Fig. 1, and

Fig. 7 is a fragmentary view shown partly in elevation and partly in cross section of structural details of my device and taken along the line 7—7 of Fig. 1.

The control device shown in the drawings, for 45 the purpose of illustrating my invention, is of the gravity feed type, adapted among other uses to control flow of oil by gravity to an oil burner (not shown) and this control device includes a casing, designated in general by the numeral 1.

The casing 1 is preferably a hollow rectangular 50 shaped casing having a bottom wall 2, side walls 3 and end walls 4, these walls cooperating to provide a reservoir chamber 5 for liquid. In the present instance, the casing 1 is a casting and has 55 an inlet chamber 6 beneath the bottom wall 2,

the inlet chamber 6 preferably being in the form of a bore. The bore or chamber 6 preferably extends longitudinally of and substantially coextensive with the casing bottom wall 2 and has an open end that opens externally of the casing at 5 one end thereof. Adjacent the open end of the chamber 6 there is provided an inlet passage thereto that may be defined by a downwardly projecting hollow boss 7 to which may be connected one end of a liquid supply line or conduit 8. 10 Preferably a strainer 10, Fig. 2, is disposed within the inlet chamber 6 for straining the liquid passing therethrough and the strainer may be tubular in shape and have a fitting provided with an external flange 11 for abutment with the casing 15 outer wall surface surrounding the open end of chamber 6. Preferably the flange 11 is clamped tightly against the casing outer wall surface by a suitable clamping means which may include a lever 12. The lever 12 may be pivoted at one 20 end to the casing 1 and be positioned to extend across and, intermediate its ends, engage the outer face of the flange 11. At its other end the lever 12 may be provided with an aperture for receiving a screw 13 that may screw-thread into 25 the casing end wall to hold the flange 11 tightly against its seat to seal the opening into chamber 6 in a fluid-tight manner. A gasket or washer 12a may be provided between the flange 11 and the outer wall surface surrounding the open end 30 of chamber 6 to insure a fluid-tight connection.

Adjacent the other end of the chamber 6, the casing bottom wall 2 is provided with a passage or bore 13a therethrough for the passage of liquid from the inlet chamber 6 into the reservoir chamber 5. Preferably the bore 13a extends through an upwardly directed, slightly extended wall portion 14 integral with the casing bottom wall 2, and opens through the upper end of portion 14 into the reservoir chamber 5. Preferably the bore 40 13a is threaded for receiving an externally threaded end portion of a tubular shaped, detachable fitting or valve seat member 15 that projects vertically upward into the reservoir chamber 5. Mounted on the upper end of the extended portion 45 14 there is a supporting member 16, preferably a U-shaped member having a base portion 17 and upwardly directed, spaced, substantially parallel side members or arms 18. The base 17 is preferably apertured substantially midway between the side members 18 to receive the tubular seat member 15 which serves to rigidly secure the U-shaped supporting member to the casing. The valve seat member 15 may be formed having an external, downwardly facing annular shoulder 55

19 for bearing against the base 17, and on opposite sides of the base 17, gaskets 20 are preferably provided to insure a leak-proof connection.

Intermediate its ends the valve seat member 15 has an internal transverse wall 21 having a bore 22 therethrough providing a valve port and an upwardly facing seat 23 for cooperation with the conical face 24 of a reciprocal valve member 25. An upper end portion of the valve member 25 projects upwardly above the upper end of the valve seat member 15, and fitted over and secured to the upper end of the valve seat member there is a cap-like guide member 27 having an aperture for slidably receiving and guiding the reciprocal valve member. In the side wall of the valve seat member 15 and above the seat 23 there may be provided one or more apertures 28 for the passage of liquid from the valve chamber into the reservoir chamber 5. Pivotaly supported on the U-shaped supporting member 16 there is a lever member 30 that is preferably formed having downturned side flanges 31 provided with aligned apertures for receiving a pivot pin 32 that may have its opposite ends secured in and to the side members 18 of the U-shaped support 16. The lever member 30 has a relatively short lever arm 33 that extends toward the valve member 25 and the end of this lever arm is preferably bifurcated or forked so as to straddle the valve member. The valve member 25 is preferably formed having a pair of spaced, external annular flanges 34 between which end portions of the bifurcated lever arm 33 position for engaging the flanges to actuate the valve. Rigidly secured to the other end of the lever 30 there is a float 35 that actuates the valve member 25 in accordance with changes in the level of the liquid in chamber 5 to maintain the level at a predetermined substantially constant level.

Within the reservoir chamber 5 and preferably integral with the casing bottom wall 2 and with one of the casing side walls 3, there is a wall means 37 that extends upwardly from the bottom wall 2 and terminates below the top of the casing 1, the wall means 37 preferably projecting inwardly from the side wall 3 intermediate the casing end walls 4. The wall 37 is provided with a vertically extending passage, preferably a bore 38 that opens through the upper face of wall 37 and constitutes a valve chamber in which a valve member 39 is disposed for reciprocal movement to control flow of liquid by gravity from chamber 5. In the side wall of the wall means 37 there may be provided a vertically extending, slot-like opening 40 to communicatively connect the reservoir chamber 5 and the valve chamber 38. The bore 38 opens into a bore 41 of relatively small diameter that is provided in a transverse internal wall 42, adjacent the casing bottom wall 2. The bores 38 and 41 are preferably axially aligned and at their intersection provide a valve port and an upwardly facing seat 43 for the valve member 39 which preferably has a downwardly facing conical face 44 for engaging the seat 43. The bore 41 preferably has a portion 45 of reduced diameter that opens through the underside of transverse wall 42 and slidably receives a lower end reduced portion 46 of the valve member for guiding the same. The reduced lower end portion 46 of the valve member 39 projects into a bore 47 that opens through the lower end of an extended portion 48, integral with and depending from the casing bottom wall 2, the bore 47 being closed by a threaded closure plug 49. An outlet opening, preferably in the

form of a bore 50, is provided and extends upwardly substantially parallel with and adjacent to the valve chamber 38 between the valve chamber and the casing side wall 3. The outlet bore 50 opens through the underside of the extended portion 48 and may be internally threaded for receiving an externally threaded end of a fuel supply line or conduit 51, the other end of which conduit may be connected to an oil burner (not shown). A transversely extending bore 52 connects the bore 47 and the outlet bore or passage 50. The bore 50 opens through the top of wall 37 into the reservoir chamber 5 at a point above the liquid level therein, and through the bore 50 gases are vented from the oil supply line to atmosphere.

The reduced portion 46 of the valve member 39 is preferably provided with a V-shaped opening or metering slot 54 in its side wall for the passage of liquid from chamber or bore 38 into passage 47 when the valve is unseated. The V-shaped metering slot 54 preferably converges upwardly from the lower end of the valve member to an apex adjacent the conical face 44 of the valve member. Oil or other liquid enters chamber 38 through opening 40 and when the valve is raised from its seat, as shown, the oil or other liquid flows into bore 41 through the upper portion of the V-shaped slot that is within bore 41, and from the V-shaped slot into bore 47 whence it passes through bores 52 and 50 into the supply conduit 51. It will be seen that when the valve is raised further from its seat so that more of the V-shaped metering slot is within bore 41, a larger quantity of liquid will be permitted to flow from the reservoir 5 to the supply conduit 51.

The top of the casing 1 is preferably open, and mounted thereon and closing the casing 1 there is a second and removable casing 55 that is preferably open at its top and bottom, the top of the casing 55 preferably being closed by a removable closure member or cover 56. The valve member 39 is of rod-like form and projects upwardly into the upper casing 55 and preferably the valve member has an upper rod portion 57 of reduced diameter that slidably engages and is guided in an aperture provided in an inwardly projecting boss or wall means 58 that may be integral with a side wall of the casing 55. The valve portion 57 of reduced diameter provides an upwardly facing annular shoulder 59 and the reduced portion 57 is formed having an annular flange 60 spaced from and above the shoulder 59, the shoulder 59 and flange 60 providing opposed, substantially horizontal abutment surfaces for a purpose to be hereinafter described.

Carried by the casing 55 and removable therewith as a unitary structure is my actuating mechanism for actuating the valve 39, and this actuating mechanism includes a thermostatic power element, designated in general by the numeral 61. The power element 61 includes a cap-like casing 62 that has an open flanged side that is disposed toward and seats against the outer surface of an end wall of the casing 55. The casing 62 may be rigidly secured to the casing 55 by screws 63, or by other suitable means. Within the power element casing 62 there is a metallic bellows 64 that has one end hermetically secured and sealed to a fixed wall or plate 65 that is disposed within the casing 62 and positioned flat against the inner surface of the end wall thereof. The other, or movable end of the bellows 64 projects into the casing 55 through an aperture in the end wall of the casing, and preferably the free end of the 75

bellows is hermetically secured and sealed to a movable wall or plate 66. Secured in and to the end wall of the power element casing 62 there is a connecting member or fitting 67 that extends through an aperture in the plate 65 and projects into the bellows, the connecting member 67 having a passage or bore 68 that opens through the inner end of the connecting member into the bellows 64. In the present instance, the bore 68 intersects another bore 69 that opens externally of the casing 62 through the side wall of the connecting member 67 and in the bore 68 is secured one end of a tube or conduit 69^a, the other end of the conduit being connected to a temperature responsive bulb element 70, Fig. 1. The power element 61 may be charged with any suitable temperature responsive, expandable-contractible fluid such as methyl chloride, and the bulb 70 is to be arranged in heat transfer relation with a heating apparatus (not shown) the operation of which is to be controlled. Surrounding the tube 69^a at the end that is connected to the connecting member 67 there may be provided a coil or wire 71 that serves to protect the tube from injury and reinforces the tube against breakage at the point of its connection to the connecting member 67.

The side walls of the casing 55 are preferably formed having oppositely disposed, inwardly directed bosses 72, see Fig. 2, and these bosses are preferably provided with aligned threaded apertures 73 therethrough and through the casing side walls for receiving adjustable supporting members or pivot pins 74. The pivot pins 74 thread into the apertures 73 from the exterior of the casing 55, and inner end portions of the pins project past the inner end faces of the bosses 72 into the casing. Preferably lock screws 76 are employed and threaded into the apertures 73 in engagement with the outer ends of the pins 74 to prevent movement of the pins from their adjusted or desired positions. The apertures 73 may be closed at their outer ends by disc-like closure members 77 that may be sprung into place in the apertures. Each of the pins 74 is provided with a recess in its outer end and the locking screws 76 are provided with pointed or conical ends to seat one in each recess. When the pins 74 have been adjusted or placed in their desired positions the locking screws 76 are then tightened down, and the pointed ends of the locking screws engaging in the recesses of the pins 74 cause the pins to expand so that the threads of the pins 74 will engage tightly with the walls of apertures 73 to prevent movement of the pins.

Disposed within the casing 55 and pivotally supported on the pins 74 there is a lever member 78 preferably of plate-like form, the lever being positioned adjacent and operatively connected to the free end of the bellows 64. The lever member 78 is formed having oppositely directed extended edge portions or arms 79, 80 that extend toward opposite side walls of casing 55, and the arm 79 is formed at its outer end having an ear 81 provided with an aperture therethrough to pivotally receive one of the pivot pins 74. The other arm, or arm 80, has an extension member or lever arm 82 that extends longitudinally of the casing toward the outer valve 39 and substantially parallel with ear 81, and this lever arm 82 is provided with an aperture therethrough for pivotally receiving the other of the pivot pins 74. An end portion of lever arm 82 positions between the opposed faces of the shoulder 59 and the

flange 60 of the valve 39 and engages said opposed faces to actuate the valve.

The movable end wall 66 of the bellows 64 is preferably cup-shaped having a central tubular portion 84 that projects into the bellows, and secured in and to the end wall of the tubular portion 84 is one section 85 of a sectionally constructed connecting rod for connecting the bellows 64 and lever 78. Disposed within the bellows 64 and rigidly secured to the inner end of the connecting member 67 there is a cap-like stop member 86 that overlies and encloses the open end of the bore 68 and this stop member 86 is arranged to cooperate with the connecting rod section 85 to limit expansive movement and prevent rupture of the bellows. It is to be understood, however, that the stop member 86 only functions as such when the power element as a unit is separate or removed from the control device. The cap-like stop member 86 has an inwardly disposed end wall provided with an aperture therethrough for receiving a reduced end portion 87 of the rod 85, the reduced portion having an enlarged portion or head 88 that is disposed for longitudinal movement within the cap-like stop member 86 and is adapted to engage the end wall thereof to limit expansive movement of the bellows 64. Surrounding the stop member 86 there is preferably provided a helical coil spring 90 that acts to expand the bellows 64, and this spring may have one end in abutment with the fixed wall 65 and the other end in abutment with the bellows movable end wall 66.

The expandable-contractible fluid for the power element is preferably introduced therewith through a bore or passage 91 provided in the connecting rod section 85 longitudinally therethrough. A filler tube 92 may be screw-threaded and sealed in the outer end of bore 91 and after the power element has been charged the filler tube may be severed and the severed end sealed by solder, or by other suitable sealing material. The end of the rod 85 that projects into the casing 55 preferably has an externally threaded reduced portion, and screw-threaded thereon is a second section 93 of the sectional connecting rod. The rod section 93 has a longitudinally extending bored recess 94 that is internally threaded for receiving the reduced end portion of rod section 85, and the end of the filler tube 92 projects into said bored recess and is enclosed by the rod section 93. The lever member 78 is formed, in the present instance, having an embossed or offset portion 95 that extends away from the bellows movable wall 66 and may be circular in shape, as shown. The offset portion 95 has an aperture 96 therethrough for receiving the rod section 93, the rod 93 projecting through said aperture at a point above the fulcrum of the lever 78, as seen in Fig. 2. The aperture 96 is preferably a vertically extending slot and the side edges defining the slot are spaced from the outer periphery of the rod 93. The side edges defining the slot 96 are provided with oppositely disposed, inwardly directed, aligned extended portions or bearing members 97, inner end portions of which engage in an annular slot or recess 98 in the rod 93, see Fig. 4. Opposite sides of the bearing members 97 are preferably rounded or have convex surfaces, as at 99, for engaging the opposed wall surfaces defining slot 98, the convex surfaces 99 reducing friction between the lineally movable connecting rod and the pivotal lever 78.

An inner end portion 100 of the rod section 93 is preferably of reduced diameter providing an 75

inwardly facing annular shoulder or seating surface 101 and a removable plate-like abutment member 102, apertured to receive the reduced portion 100, seats against the shoulder 101. A 5 helical coil spring 103 surrounds the reduced end portion 100 and has one end abutting the abutment member 102 and its other end abutting a similar but movably adjustable abutment member 105. The spring 103 is held under compression 10 between the abutment members 102 and 105 and exerts a force opposing the power element and acting to pivot lever 78 in a counterclockwise direction, as seen in Fig. 5.

The adjustment means for regulating the force 15 exerted by the spring 103 is carried by the casing 55 and supported by the vertical wall thereof, opposite the power element, this wall being designated by the numeral 106. The wall 106 is preferably formed having an inwardly projecting 20 boss 107 provided with a bore 108 therethrough, the longitudinal axis of bore 108 being substantially in alignment with the axis of the bellows 64 and the spring 103. Preferably the bore 108 has an outer end threaded portion 109 of reduced 25 diameter that opens through the casing wall 106, and adjustably screw threaded into bore 109 is the spring adjusting means which preferably includes a tubular member 110 having an external threaded portion 111 intermediate its ends for 30 screw threading into bore 109. An outer end portion of the tubular member 110 projects externally of the casing 55 and secured to said outer end portion there is preferably a knob 112 or other suitable means for conveniently rotating 35 the member 110.

The spring adjustment means includes a thrust rod 113 that is carried by and is adjustably screw threaded into the tubular member 110. An outer end portion 115 of the thrust rod 113 is preferably of enlarged diameter and externally threaded for screw threading into the tubular member 110, the tubular member preferably having a reduced bore portion at its inner end for slidably receiving and guiding the thrust rod 113. Preferably a locking screw, as at 116, is screw threaded 40 into the outer end of the tubular member 110 and has a pointed end that positions in a recess in the outer end of thrust rod 113. After the thrust rod 113 has been adjusted to its desired position the locking screw 116 is tightened and the pointed end thereof engaging in the recess of the rod 113 expands the rod circumferentially so that the outer periphery of the rod tightly engages the wall of the threaded aperture to thereby prevent 45 loosening of the rod. The thrust rod 113 projects beyond or extends past the inner end of the tubular member 110 and the movable adjustment member 105 is provided with a central aperture therethrough for receiving a reduced end portion 117 of the rod 113, the reduced portion 117 providing an inwardly facing annular shoulder for seating against abutment member 105. The reduced portion 117 extends centrally through the coil spring 103 into a bored recess 120 provided in 50 the connecting rod section 83 longitudinally thereof, and the thrust rod serves to limit lateral movement of the connecting rod and associated parts.

Integral with the end wall 106 of casing 55 70 there is a pair of horizontally spaced lugs or bosses 122 that project into the casing toward the opposite end wall thereof, and these bosses are preferably located adjacent the upper end of the casing and positioned one adjacent each 75 of the opposite side walls thereof. A pair of

plate-like lever members 123 and 124 are pivotally supported, one on each of the lugs 122, and extend therefrom substantially parallel with each other toward the opposite end wall of the casing 55. The lever members 123, 124 may be formed at their pivoted ends having spaced, substantially horizontal and parallel ears 125 between which the lugs 122 position, and the ears and lugs may be provided with aligning apertures to receive vertically disposed pivot pins 126 10 for pivotally connecting the levers to the supporting lugs 122. The levers 123, 124 are thus supported for pivotal movement in planes substantially transverse to the plane of movement of lever 78 about its fulcrum. The lever 78 is 15 formed having an upwardly directed arm 127 that is preferably formed at its upper end having an ear or flange portion 128 that is disposed substantially midway between and extends substantially parallel with levers 123, 124, toward 20 end wall 106. The flange portion 128 is provided with an aperture therethrough in which a bearing member 130 is positioned and rigidly secured to the flange portion, and this bearing member is provided with sockets or conical recesses 131 in its opposite faces or ends. The free ends of the levers 123, 124 position on opposite sides of the arm flange portion 128 and are provided with inwardly facing sockets or conical recesses 133. The levers 123, 124 are connected to lever 78 by thrust members 134, preferably rods or pins, which terminate at their opposite ends in conical points 135 seating in the pairs of sockets 131 and 133. The pins 134 are held in the sockets in engagement with 30 levers 123, 124 by a tension spring 136 secured at its opposite ends to the levers 123, 124, urging the levers toward each other. The spring 136 is preferably of the helical coil type terminating at its ends in hooks 137, one of which cooperates in holding relation with a U-shaped loop member 138 connected to and carried by the lever arm 123. The other hooked end of the spring 136 positions in an aperture in an adjustment member 139 that is carried by the lever 40 45 124 and by means of which adjustment member the tension force of spring 136 may be regulated as desired. The adjustment member 139 may be in the form of a screw that may be threaded into an internally threaded tubular supporting member 140 secured in and to the lever 124. The sockets 133 of the levers 123, 124 are substantially in alignment with each other, but the sockets 131 of the lever 78 are preferably slightly out of alignment with the sockets 133 when 50 the valve 39 is in open position so that the pins 134 are slightly angularly disposed with their inner ends positioned closer to the power element than their outer ends, as shown in Fig. 1. The coil spring 136 exerts a force acting through 55 levers 123, 124 and pins 134 tending to pivot lever 78 in a counterclockwise direction, as seen in Fig. 5. When the combined forces exerted by the springs 136 and 103 are overcome by the power element, the valve 39 will be actuated 60 with a snap action by the power element. The temperature at which the power element will overcome the springs 136 and 103 may be determined, or selected, by adjusting the force exerted by the spring 103, and preferably indicating means such as a pointer 141 is provided and actuated by the spring adjustment means for indicating and aiding in setting the device to operate at a desired temperature.

At its inner end the hollow boss 107 is formed 75

having an extended, substantially horizontal, external wall portion 142 that is integral with and projects laterally from the side wall of the boss, and this wall 142 has a vertically extending bore therethrough for receiving a shaft 143 that is journaled for rotation in the bore. A lower end portion of the shaft 143 preferably projects below the underside of wall 142 and a pinion gear 144 is secured to the lower end of the shaft 143 for rotation therewith. The shaft 143 may be formed having a downwardly facing annular shoulder 145 for seating on the upper surface of wall 142, as shown. Formed on an inner end portion of the tubular adjustment member 110 there is a gear rack 146 positioned for longitudinal movement within bore 108, and the side wall defining bore 108 is provided with an opening therethrough, below wall 142, to permit engagement between the rack 146 and gear 144. The rotatable shaft 143 extends vertically upward from the boss 107 and an upper end portion of the shaft may be of reduced diameter, as at 148, and be positioned in an aperture in the cover 56 to steady the shaft. The pointer 141 may be secured to the shaft 143 within casing 55, adjacent the underside of the cover 56, and at its free end the pointer 141 may have an upturned end portion 149 for movement in an arcuate slot 150 provided in the cover 56. On the outer or upper face of the cover 56 suitable indicia (not shown) may be provided for cooperation with the pointer 141 to indicate the setting of the device.

Adjustably screw threaded into the wall 58 there is a pair of spaced, laterally positioned, adjustable stop members 151 and 152 for limiting movement of the valve 39. The stop members 151 and 152 project below the underside of the wall 58 and at their lower ends preferably have external annular flanges 153, 154 respectively, for abutment with the annular flange 60 of the valve 39. The valve 39 extends between and longitudinally of the stop members 151, 152 and the stop member 151 is arranged to limit movement of the valve in a valve opening direction, while the stop member 152 limits movement of the valve in a valve closing direction. A plate member 155, preferably formed of spring sheet metal, is apertured to receive the stop members 151, 152 and is clamped flat against the underside of wall 58 by nuts 155^a that thread onto the stop members. The plate member 155 has downturned flanges 156 that engage with one of the flattened sides of the nuts to prevent rotation of the nuts and the flanges and also act to increase friction between the stop members 151, 152 and the nuts so that the stop members will be held against accidental movement. Resilient or spring means, preferably lock washers as at 158, are provided one between each of the nuts 155^a and the plate member 155 to increase the resistance to movement or turning of the screw threaded stop members so that their adjustment will not be altered accidentally or through vibrations of the device. I have found that by tightening down the nuts 155^a as far as they will go, and then turning the nuts back approximately a quarter of a turn it will permit the adjustable stop members to be easily adjusted and yet sufficient resistance to rotation of the stop members will be had to prevent their accidental movement.

The operation of my device is as follows: When the temperature of the bulb 70 is at, or below a predetermined temperature, the lever 78 will be

in the position shown in the drawings and the springs 103 and 136 will hold the valve 39 in an open position. Oil will flow from the reservoir chamber 5 through the valve port 43, passages 52, 50 and the supply conduit 51 to an oil burner of a heating apparatus. As the temperature of the heating apparatus increases, the fluid in bulb 70 expands exerting a force on the bellows 64 tending to expand the bellows. This force builds up and when it exceeds the force exerted by the springs 103 and 136 the lever 78 will be pivoted in a clockwise direction, as seen in Fig. 5, and the valve 39 will be moved toward closed position, limited by the stop member 154. The stop means 151 and 152 may be adjusted so as to obtain a desired maximum flow capacity when the valve 39 is engaging the stop 151, and a desired minimum flow capacity when the valve is engaging the stop member 152. When the valve 39 is moved to the minimum flow position the temperature of the bulb 70 decreases with corresponding decrease in the force exerted by the power element. When the force exerted by the power element becomes less than the force exerted by the springs 103 and 136 these springs will pivot the lever 78 in a counterclockwise direction, as seen in Fig. 5, moving valve 39 toward open position to increase the quantity of fuel flow to a burner.

What I claim and desire to secure by Letters Patent of the United States is:

1. In a control device having a movable controlling means, an actuating mechanism for said controlling means comprising a power element operable positively to move said controlling means in one direction, a lever member movable by and with said power element and operable to transmit directly the force of said power element to said controlling means, yieldable means acting on said lever member and operable to move said controlling means in the opposite direction, a lever member separate from said first-named lever member and fulcrumed to pivot in a plane substantially transverse to the plane of movement of said first-named lever member, a thrust member connecting said lever members, and yieldable means acting on said separate lever member and exerting a force through said thrust member against said first-named lever member to oppose movement of said controlling means by said power element.

2. In a control device having a movable controlling means, a plate-like lever for moving said controlling means and having an aperture therethrough, a power element including a bellows member disposed on one side of said lever and operable to pivot said lever in one direction, a connecting member for operatively connecting said bellows member and said lever and extending through said aperture, said connecting member having a recess therein on the other side of said lever, a coil spring surrounding said connecting member on the said other side of said lever and having one end acting against said lever, said coil spring exerting a force operable to pivot said lever in the opposite direction, a movable abutment member for the other end of said spring and having an aperture therethrough, and manually operable means for moving said abutment member to regulate the force of said spring and extending through said aperture into said recess for guiding said connecting member.

3. In a control device having a controlling means and an actuating means therefor, a plate-like lever member for operatively connecting the controlling means and the actuating means, a

supporting means for pivotally supporting said lever member, said lever member having an aperture therethrough and having a bearing member extending substantially transverse to the plane 5 of movement of said lever member about its fulcrum, and a linearly movable thrust member for connecting the actuating member and said lever member, said thrust member extending through said aperture and having a socket for receiving 10 said bearing member.

4. In a control device having a controlling means and an actuating means therefor, a plate-like lever member for operatively connecting the actuating means and the controlling means, a 15 supporting means for pivotally supporting said lever member, said lever member having an aperture therethrough with the wall defining said aperture having a pair of oppositely disposed inwardly directed extended portions, and a linearly 20 movable thrust member actuated by the actuating means and extending through said aperture, said thrust member having sockets for receiving said extended portions to rock said lever member with said sockets having opposed bearing surfaces, said extended portions having opposed face 25 portions convexly formed for rocking engagement with the opposed bearing surfaces of said sockets.

5. In a device of the character described, a supporting member, a controlling means, a stop member for said controlling means and adjustably screw-threaded into said supporting member, a nut screw-threaded onto said stop member, resilient means held under tension by said 35 nut to increase the resistance to movement of the stop member, and a plate member held to said supporting member by said nut and having a flange portion positioned relative to said nut to prevent rotation of said nut.

40 6. In a control device having a movable controlling means, a lever for moving said controlling means, a power element operable to pivot said lever in one direction, a connecting member for connecting said power element and said lever, a coil spring surrounding said connecting member 45 and having one end acting against said lever, said coil spring exerting a force operable to pivot said lever in the opposite direction, a movable abutment member for the other end of said spring and having an aperture therethrough, and manually 50 operable means for moving said abutment member to regulate the force of said spring and extending through said aperture and guiding said connecting member.

55 7. A control device comprising a fixed supporting means, a lever member having a pair of substantially parallel arms pivotally connected to said supporting means and having a third arm positioned between said parallel arms, actuating means operable to pivot said lever member, a 60 movable controlling means operatively connected to and movable by one of said parallel arms, a pair of lever members pivotally mounted on said fixed supporting means, a thrust member extending 65 from the free end of one of said pair of lever members and engaging said third arm, a thrust member extending from the free end of the other of said pair of lever members and engaging said third arm, and yieldable means urging said pair 70 of lever members toward each other and acting through said thrust members to pivot said first-named lever member in one direction and oppose said actuating means.

75 8. A control device comprising a fixed supporting means, a lever member having a pair of

substantially parallel arms pivotally connected to said supporting means and having a third arm positioned between said parallel arms, actuating means operable to pivot said lever member, a movable controlling means operatively connected 5 to and movable by one of said parallel arms, a pair of lever members pivotally mounted on said fixed supporting means and extending one on either side of said third arm, said pair of lever members being in a substantial horizontal plane 10 intersecting said third arm, a thrust member extending from the free end of one of said pair of lever members and engaging said third arm, a thrust member extending from the free end of the other of said pair of lever members and engaging said third arm, and spring means urging 15 said pair of lever members toward each other and acting through said thrust members to pivot said first-named lever member in one direction and oppose said actuating means. 20

9. In a device of the character described, a substantially rectangular casing having oppositely disposed end walls and side walls, one of said end walls having an aperture therethrough, a power element secured to said one end wall external 25 of said casing and having a portion thereof projecting through said aperture and within said casing toward the other of said end walls, a helical coil spring longitudinal of said casing and having one end engaging said power element 30 projecting portion, said other end wall having a threaded aperture therethrough, manual adjusting means extending from the exterior of said casing and threaded within said threaded aperture and having a portion thereof engaging the 35 other end of said spring and operable to hold said spring under compression against said power element, a lever member positioned laterally of said casing and pivotally supported on said casing side walls and engaged by said power element, and a 40 pair of lever members hinged at one end thereof to said other end wall and having the extended ends thereof extending substantially longitudinally of said casing, said lever member having a portion thereof projecting between said pair of lever members, a thrust member connecting one of said pair of lever members and said first-named lever member portion, a second thrust member connecting the other of said pair of lever members and said first-named lever member portion, a helical coil spring operable to urge said 45 pair of lever members together, and valve means engaged and operated by said first-named lever member. 50

10. In a device of the character described, a substantially rectangular casing having oppositely disposed end walls and side walls, one of said end walls having an aperture therethrough, a power element secured to said one end wall external of said casing and having a portion thereof projecting through said aperture and within said casing toward the other of said end walls, a helical coil spring longitudinal of said casing and having one end engaging said power element 55 projecting portion, said other end wall having a threaded aperture therethrough, manual adjusting means extending from the exterior of said casing and threaded within said threaded aperture and having a portion thereof engaging the other end of said spring and operable to hold 60 said spring under compression against said power element, a lever member having a pair of substantially parallel arms pivotally connected to said casing side walls and engaged by said power element, a pair of lever members hinged at one 65

end thereof to said other end wall and having the extended ends thereof extending substantially longitudinally of said casing, said first-named lever member having a third arm positioned substantially midway and extending upward between said pair of lever members, a thrust member connecting one of said pair of lever members and said third arm, a second thrust member

connecting the other of said pair of lever members and said third arm, a helical coil spring operable to urge said pair of lever members together, and valve means operable for vertical movement and engaged and operated by one of said pair of parallel arms.

WALTER S. LANDON.
